Primary Examiner — Sharon S Oum*Assistant Examiner* — Raylen E Worthington(74) *Attorney, Agent, or Firm* — Jose Cherson Weissbrot(57) **CLAIM**

The ornamental design for a solar deck light, as shown and described.

DESCRIPTION

FIG. 1 is a perspective view of a solar deck light, showing my new design in an open state;

FIG. 2 is another perspective view thereof;

FIG. 3 is a front elevational view thereof, the rear elevational view is identical;

FIG. 4 is a left elevational view thereof, the right side view is identical;

FIG. 5 is a top side view thereof; and,

FIG. 6 is a bottom plan view thereof.

The broken lines in the figures are for the purposes of illustrating portions of the solar deck light, which form no part of the claimed design.
